UNITED STATES PATENT OFFICE

2,123,994

RECORD STRIP CONTROL FOR AUTO-
GRAPHIC REGISTERS

Louis Fred Hagemann, Niagara Falls, N. Y., assignor to American Sales Book Company, Inc., Elmira, N. Y., a corporation of Delaware

Application April 10, 1935, Serial No. 15,618

7 Claims. (Cl. 282—16)

This invention relates to autographic registers, and more particularly to mechanism adapted to feed record strips and to direct and retain one or more strips in a storage compartment.

5 An important object of this invention is to provide new and improved mechanism which will facilitate the insertion of the record strips in the initial threading operation, and which will operate satisfactorily to divert and retain one strip 10 within the closed compartment.

Another object is to provide an improved arrangement for a deflector plate for diverting one or more of the feed record strips into the storage compartment, said deflector plate being mounted 15 in a novel manner to provide for retraction to facilitate threading of the strips into operative position, and having an improved retaining device to hold it in its operative strip-diverting position.

20 A further object is to produce a device of the character described, which will be simple and efficient in operation and inexpensive in manufacture.

Other objects of the invention will be in part 25 obvious and will in part appear hereinafter.

The invention accordingly comprises the features of construction, combinations of elements and arrangement of parts, which will be exemplified in the construction hereinafter set forth 30 and the scope of the application of which will be indicated in the claims.

For a more complete understanding of the nature and objects of the invention reference should be had to the following detailed description taken in connection with the accompanying 35 drawing, in which:

Fig. 1 is a fragmental longitudinal vertical section of a machine embodying the invention, parts being shown in elevation;

40 Fig. 2 is a fragmental side elevation on a smaller scale;

Fig. 3 is a section along the lines 3—3 of Fig. 1; and

Fig. 4 is a plan view of the file record strip.

45 Certain of the subject matter of this application is disclosed in applicant's prior application Serial No. 62,974, filed October 17, 1925, for Autographic register, patented June 4, 1935, Patent No. 2,003,999. The present application, therefore, 50 is a continuation in part of the earlier application.

In the drawing, a casing 1 preferably has at one end thereof a supply compartment 2 adapted for the reception of a multiple strip record support 3 in the usual manner. At the top of the 55

casing is provided a tablet 4 over which the strips are adapted to be fed by a feeding mechanism, which will be later described. A margin frame 5 is pivoted to the side of the casing in position to overlie the tablet. A suitable housing 6 5 may be provided for retaining transfer sheets 7 in position to be inserted between the strips as they pass over the tablet. The strip supply may be conveniently in the form of a flat pad composed of a plurality of superposed strips S 10 folded zigzag upon one another, and the strips are guided over the tablet and the transfer sheets in any suitable manner. The strips, one of which is shown in Fig. 4, are preferably formed with feed controlling apertures 8 arranged in one or 15 more longitudinal series, and the file strip also has a longitudinal series of fold-directing apertures 9, one of which is positioned in each alternate form sheet of the strip.

The feed mechanism comprises a roll 10 and 20 cooperating disks 11 which are geared together. The roll is journaled in a housing 12 carried by arms 13 pivoted to the casing 1 at 14. In order to permit movement of the roll toward and from the disks 11, the bearing pivots 15 of the roll 25 move in slots 16 in the side walls of the housing, while springs 17 urge the pivots downwardly toward the bottom of the slots. In this manner when the housing is in its closed position as shown in Fig. 1, the roll is urged downwardly 30 toward the disks 11. Spring-pressed catches 18 carried by the housing 12 engage pins 19 to hold the roll 10 in engagement with the disks 11.

The disks 11 are carried by a main feed shaft 20 operated by a handle 21 while a spring pressed 35 stop 22 stops the handle at the completion of the feeding movement. A gear 22 may be connected to drive the roll 10.

At the end of the casing opposite to the supply compartment, there is provided a record compartment 24 having a cover 25 hinged to the end wall of the casing, as shown at 26. This cover is retained in place by catches 27 upon the side walls of the casing 1, and is adapted to be retained closed by a lock 28 which may conveniently be arranged to engage one of the catches 21 to restrain its operation.

For the purpose of diverting the lower record strip into the record compartment, and for directing the other sheets upwardly over the cover 50 of the record compartment, a guide plate or strip diverter 29 is arranged to be movable from a substantially horizontal position just beyond the feeding mechanism to a raised position to permit the ready insertion of the end of the lower 55

record strip into the compartment 24. This movement is accomplished by pivoting this diverter plate to the casing through one or more brackets 30 attached to the diverter. This pivot 5 may conveniently be the same as the pivot 14 around which the housing moves, the housing 12 and diverter 29 being concentrically pivoted at a point forwardly of the feed mechanism. Threading of the strips into position in the feed 10 mechanism is thus facilitated.

By arranging the guide plate 29 in the manner described, it will be seen that it lies in a position beneath the housing 12 so that access to it cannot be had except upon movement of the 15 housing. The housing, moreover, is so arranged that when in its lowered position, it prevents all access to the record strip at and beyond the feeding mechanism, insuring that the strip shall enter the record compartment and preventing its removal 20 from the compartment in an unauthorized manner.

Moreover, the housing is also preferably so arranged as to prevent the removal of the tablet 4. This may readily be accomplished by placing one 25 of the retaining screws of the tablet 4 beneath some portion of the housing. The cover 25 of the record compartment is shaped to provide one or more shoulders 31 positioned to engage the seats 32 in the side arms 13 of the housing 12 to 30 prevent the lifting of the housing while the cover is closed.

This register, in the form just described, is intended for use with record strips S having forms 33 printed thereon, and feed control apertures 8 35 in registry with the forms. The feed is controlled and the registry of a form on one strip with the corresponding forms on the other strips is maintained by cooperation of the disc 11, the roll 10 and the control apertures referred to, in a 40 manner well known in the art, and described in the Johnston Patent No. 1,658,127, issued February 7, 1928.

For the purpose, moreover, of refolding the lower record sheet S within the locked compartment 24, a selecting disk 34, as shown in the Johnston patent mentioned, may also be mounted upon the shaft 20 carrying a finger 35 which is pressed upwardly by a spring 36, but depressed by a cam 37, as the finger during the rotation of the 50 disk is brought up to the position opposite the record strips. An auxiliary line of fold controlling apertures 9, for folding cooperation with the folding finger 35, is provided in the record strip, these apertures appearing in each alternate record sheet of the strip in registry with the form 55 thereon.

In threading the machine, the record strips are carried out of the end of the casing and over the writing tablet 4, the appropriate carbons being interleaved between them. The cover 25 of the record compartment may now be thrown back by releasing the catches 21 and the housing 12 may be raised by releasing the catches 18. Thereupon the guide plate 29 may be lifted and the end of the lower record strip directed beneath it. The 60 guide plate 29 may then be turned back into its horizontal position and the remaining record strips inserted over it. The housing 12 may now be lowered and latched and then the cover 25 of the record compartment may be closed and locked, and the margin frame 5 fastened in place. The forward wall of the housing 12 overlies the diverter plate 29 when closed, so as to engage with and prevent movement of said plate from its normal 70 operative position of Fig. 1, into its strip 75

threading position shown in Fig. 2, and the cover 25 may also engage the diverter as shown to hold the latter in its operative position.

With the machine arranged as above described, the turning of the handle 21 will feed the record strips together the length of one record form. The upper strips will be fed out of the machine in position to be grasped by the hand, while the lower sheet will be diverted into the locked compartment 24 and refolded there in zigzag form. 10

Since certain changes may be made in the above construction and different embodiments of the invention could be made without departing from the scope thereof, it is intended that all matter contained in the above description, or shown in the accompanying drawing, shall be interpreted as illustrative and not in a limiting sense.

Having described my invention, what I claim as new and desire to secure by Letters Patent is:

1. An autographic register including, in combination, record strip feeding mechanism including a feed roll, a roll carrier pivotally mounted so as to carry said roll to and from strip feeding position, and a strip diverter separate from the roll carrier and pivotally mounted substantially coincidentally with said roll carrier. 20

2. An autographic register including, in combination, record strip feeding mechanism including a feed roll, a roll carrier pivoted on an axis disposed forwardly of the feeding mechanism and substantially parallel to the axis of said feed roll, and a strip diverter separate from the roll carrier and pivoted on an axis substantially coincident with the pivotal axis of said roll carrier. 30

3. An autographic register including, in combination, record strip feeding mechanism including a feed roll, a roll carrier pivotally mounted so as to carry said roll to and from strip feeding position, and a strip diverter separate from the roll carrier and pivotally mounted substantially coincidentally with said roll carrier, and means cooperating with said diverter for retaining the latter in its operative strip diverting position. 40

4. An autographic register including, in combination, record strip feeding mechanism including a feed roll, a roll carrier pivoted on an axis disposed forwardly of the feeding mechanism and substantially parallel to the axis of said feed roll, a strip diverter separate from the roll carrier and pivoted on an axis substantially coincident with the pivotal axis of said roll carrier, and a retaining device positioned for engagement with said diverter for retaining the latter in its operative strip diverting position. 50

5. In a machine of the character described, in combination, a record strip feeding mechanism including a feed roll pivoted to swing about an axis disposed forwardly of the roll and substantially parallel to the longitudinal axis of said roll, a strip diverter mounted for movement away from normal operative position into position to facilitate insertion of a record strip beneath it, retaining means for holding the feed roll in operative feeding position, and a cover for a compartment of the machine engageable with said diverter when the cover is in closed position for holding said diverter in its operative strip diverting position. 60

6. In a machine of the character described, in combination, a record strip feeding mechanism including a feed roll pivoted to swing about an axis disposed forwardly of the roll and substantially parallel to the longitudinal axis of said roll, a strip diverter pivotally mounted on an axis dis- 70

posed forwardly of the roll, retaining means for holding the feed roll in operative feeding position, a record compartment for receiving strips controlled by said diverter and a cover for said compartment engaging said diverter to retain it in its operative position.

7. In a machine of the character described, in combination, a record strip feeding mechanism including a feed roll pivoted to swing about an axis disposed forwardly of the roll and substan-

tially parallel to the longitudinal axis of said roll, a strip diverter mounted for movement away from normal operative position into position to facilitate insertion of a record strip beneath it, retaining means for holding the feed roll in operative feeding position, a record compartment for receiving strips controlled by said diverter and a cover for said compartment engaging said diverter to retain it in its operative position. 5

LOUIS FRED HAGEMANN. 10
